UNITED STATES PATENT OFFICE.

NORBERT J. STRODEL, OF SYRACUSE, NEW YORK.

VALVE LIFTER.

Application filed July 2, 1924. Serial No. 723,723.

This invention relates to a device for compressing retracting springs of valves for internal combustion engines to permit said valves to be more easily removed for cleaning, regrinding and other repairs when necessary.

These devices are commonly known as "valve lifters" and generally consist of a pair of hand levers pivoted to each other and provided with cooperative jaws adapted to be wedged between the spring seat and underlying portion of the frame so that when opened, the spring seat will be moved axially lengthwise of the valve rod against the action of its retracting spring to permit the removal of the usual stop pin and valve, but most of these devices with which I am familiar involve the use of three or more parts with more or less complicated mechanisms for adjusting the jaws in place and for locking the levers in their open positions.

The main object of my present invention is to provide a two-part valve lifter in which both parts are made of comparatively light steel bars or rods which may be easily and quickly forged to the desired form and in which the interlocking connections for holding the jaws open form integral parts of the handles at the extreme ends thereof where the leverage is greatest and the holding power required, the least.

Another object is to make both of the jaws substantially alike and tapered or wedge-shaped and comparatively thin so that they may be more easily forced between the spring seat and underlying portion of the engine frame preparatory to compressing the spring for releasing the valve.

Other objects and uses relating to specific parts of the device will be brought out in the following description.

Figure 1 is a side elevation, partly in section, of a valve lifting device embodying the various features of my invention and shown in operative connection with the valve and adjacent portions of an internal combustion engine.

Figure 2 is an enlarged transverse sectional view of the same device taken on line 2-2, Figure 1.

Figure 3 is a detail sectional view taken on line 3-3, Figure 1.

In order that this invention may be clearly understood, I have shown a portion of an internal combustion engine —A— and one

of the port-controlling valves —B— having the usual stem —b— guided in a suitable opening —a— in the portion of the engine frame —A—.

The lower end of the valve is adapted to 60 be engaged by the usual cam-operated tappet —C— which is guided in a suitable opening —a'— in the engine frame —A—.

The valve stem is provided near its lower end with the usual removal stop pin —b'— 65 and seat —d— for receiving the lower end of a coil spring —D— which surrounds the valve stem and has its upper end seated against the under side of the portion of the frame —A— in which the guide opening 70 —a— is formed.

The spring seat —d— for the lower end of the spring is movable axially and is limited in its downward movement by the pin —b'— which also serves to limit the upward 75 movement of the valve —B—.

It is evident however, that by removing the pin —b'—, the valve —B— may be removed by upward displacement for repairs 80 when desired.

The valve lifter forming the subject matter of my invention is adapted to lift the spring seat —d— against the action of the spring —D— to permit the removal of the pin —b'— and valve —B— and for this purpose is made in two similar L-shaped parts or angle levers —1— and —1'—, superposed one upon the other and having the portions thereof near the angles as —x— and —y— provided with overlapping lugs —2— 85 and —2'—, the adjacent faces of each lug being recessed to receive the other lug and both lugs are pivoted to each other by a pivotal pin —3—.

This pivotal pin constitutes a fulcrum 95 about which both levers are adapted to rock so that the handle portions are relatively long and straight while the jaw portions as —4— and —4'— are relatively short to enable the spring to be easily compressed 100 by the application of a relatively small amount of power to the outer ends of the handles.

The jaw portions —4— and —4'— of the levers are offset in the same direction from the handle portion thereof, and are preferably flat and tapered toward their free ends which are provided with lengthwise slots —5— and receiving the adjacent portion of the valve stem —b— when the jaws 110

are wedged between the spring seat —d— and underlying portion of the frame of the engine as shown in Figure 1.

In other words, the jaws —4— and —4'— 5 are of similar taper and when closed, constitute a tapered wedge to enable them to be more easily inserted between the spring seat —d— and underlying portion of the engine frame.

10 The outer end of the handle of the lever —1'— is provided with a laterally offset hook-shaped extremity —6— forming an integral part thereof and projecting therefrom toward the corresponding end of the lever —1— which is preferably round in cross section at its point of engagement with its hook-shaped member —6— so that when the jaws —4— and —4'— are opened in the act of lifting the spring seat —d— against the action of the spring —D—, the hook-shaped extremity —6— will be brought into interlocking engagement with the corresponding end of the lever —1— for holding the jaws in their open positions, thus permitting the removal of the stop pin —b'— and valve —B—.

Owing to the length of the handles of the levers from their fulcrum pivot —3—, the free ends thereof may be readily sprung laterally relatively to each other to permit the interlocking engagement of the hook —6— with the corresponding end of the lever —1—.

35 The free ends of the levers —1— and —1'— move about the axis of the pivot —3— in substantially the same plane and the end of the hook —6— is disposed in the path of movement of the free end of the lever —1— so that when the handles of the lever are closed in the act of lifting the spring seat —d— against the action of the spring —D—, the free ends of the handles of the levers —1— and —1'— will have to be sprung laterally relatively to each other

a sufficient distance to permit the free end 45 of the handle of the lever —1— to enter the recess as —6'— in the hook —6— where it is held by the free end of said hook against accidental opening.

In releasing the jaws from their open positions, the free ends of the handles of the levers may be sprung laterally to disengage the free end of the lever —1— from the recess —6'— of the hook —6— thus permitting the handles of the levers to be opened 55 when the jaws —4— and —4'— are closed by the distention of the spring —D—.

What I claim is:

A valve lifting device comprising similar inner and outer levers, each comprising a 60 relatively long straight handle portion and a relatively short straight wedge-shaped jaw portion longitudinally bifurcated and extending at an obtuse angle to the handle portion, said handle portions having pivotally connected lateral ears thereon adjacent to but slightly spaced from the juncture of the handle and jaw portions, whereby the levers are pivotally connected in non-crossed relation so as to permit positioning 70 of the jaws horizontally in substantially flatly contacting relation for being readily wedged between the lower abutment of a valve stem spring and an adjacent fixed part, with the handle portions positioned at 75 a nearly vertical upward and outward inclination and in slight upwardly diverging relation, for being grasped to press the handle portion of the inner lever outwardly and downwardly toward the handle portion of the outer lever and to thereby raise the jaw portion of the inner lever away from the jaw portion of the outer lever and compress the valve stem spring.

In witness whereof I have hereunto set 85 my hand this 12th day of June, 1924.

NORBERT J. STRODEL.
